UNITED STATES PATENT OFFICE.

ROBERT H. BOGERS, OF SCHENECTADY, NEW YORK, ASSIGNOR TO GENERAL ELECTRIC COMPANY, A CORPORATION OF NEW YORK.

AUTOMATIC STEERING APPARATUS.

Application filed March 18, 1922. Serial No. 544,945.

My invention relates to automatic steering apparatus for dirigible craft, such as ships and the like, and has for its object the provision of simple, reliable and efficient means whereby such craft may be automatically steered along a predetermined course.

In the steering of a dirigible craft, for example, a ship, along a straight course by manual or manually controlled means, the ship ordinarily takes a zig-zag path due to improper judgment by the helmsman of the amount of deviation of the ship to be corrected. The effect of this is to lengthen the path of the ship, check its speed and periodically throw an overload on the propeller and propulsion machinery. It follows that the time taken by the ship in traveling from port to port is materially greater than if the ship were caused to follow a straight course. Furthermore, the efficiency of the propeller and propulsion machinery is decreased, and it is also practically impossible to calculate the distance traveled from the propeller turns.

By means of my invention I am able to counteract at its inception any tendency on the part of the ship to swing off its course. In carrying out my invention I provide means responsive to both deviation and positional displacement of the ship with relation to the water for controlling the rudder so as to return the ship to a predetermined course. In one form of my invention I employ a drag towed from the ship by a line of considerable length. This line identifies any course along which the ship may be set by manual control, and any turning of the ship from this course under the inboard end of the line is instantly apparent. Control means are associated with the drag line in such manner that the rudder is automatically moved in response to the ship's swing in a direction to counteract such swing. My invention is adaptable to various systems for actuating a ship's rudder whether mechanical, steam, electrical, hydraulic or a combination of such systems. By properly proportioning the drag to give the necessary pull, the tension on the line may be utilized directly as the rudder actuating force.

For a more complete understanding of my invention reference should be had to the accompanying drawing in which Fig. 1 is a

plan view of automatic steering means for 55 a ship embodying my invention; Fig. 2 is an elevation view showing the operating connection between the servo motor and the control for the rudder actuating means; Fig. 3 is an elevation view of the control device associated with the drag line; Fig. 4 is a plan view of a ship provided with automatic steering means embodying my invention; Fig. 5 is a diagrammatic view showing the control system for the electric servo 60 65 motor; Figs. 6 and 7 are diagrammatic views showing a simplified form of my invention; while Fig. 8 is a plan view showing a modified form of my invention.

Referring to Fig. 1 of the drawing, although I have shown my invention in one form as applied to a well known electric hydraulic system for operating the rudder, which will be described only in general, it will be understood that my invention is 70 75 equally applicable to various other rudder operating systems. The particular system shown comprises a hydraulic plunger 10 operatively connected at its center to the tiller 11 and having its ends moving in opposed hydraulic cylinders 12 and 13 which are supplied with a suitable liquid through pipes 14 and 15 by a pump 16 continuously driven by an electric motor 17. The pump 16 is driven at a constant speed, and the 80 85 pressure of the liquid supplied by it to cylinders 12 and 13 may be varied by means of a control rod 18 so as to move piston 10 as desired to adjust the position of the rudder.

Control rod 18 is actuated in response to 90 movement of wheel 20 by the pilot through a hydraulic device of a suitable well known form. This hydraulic device is shown as consisting of two hydraulic cylinders 21 and 22, the plungers of which are provided with 95 racks cooperating with a pinion on the shaft of wheel 20 so that as the wheel is turned in one direction or the other, as the case may be, one of the plungers is depressed while at the same time the other is raised a corresponding amount. Cylinders 21 and 22 are connected through pipes 23 and 24 to tubular, fixed, aligned plungers 25 and 26, respectively, operating with aligned cylinders in a movable member 27. It will be 100 105 observed that movement of wheel 20 causes unbalanced hydraulic pressures in the cylinders of member 27, thereby causing the

member to move to equalize these pressures and repeat in terms of translation the movement of the wheel.

Member 27 is connected through a link 28 provided with a centering spring 29 of well known form to a lever 30 pivotally attached at or near its center to control rod 18. The left hand end of lever 30 is connected through a link 31 to tiller 11. Movement 10 of member 27 in response to movement of wheel 20 is thus transmitted to control rod 18 whereby pump 16 is caused to actuate plunger 10 in a corresponding direction, the movement of plunger 10 being transmitted 15 through link 31 to lever 30 so as to return control arm 18 back to its off position. In this manner movement of wheel 20 by the helmsman is transmitted and applied automatically to tiller 11 to adjust the position 20 of the rudder.

Referring to Figs. 1 and 4, in accordance with my invention I have provided a drag line 35 having on its end a small drag 36, which line is attached to the end of an arm 25 37 on the ship. Cooperating with the drag line, so as to be actuated upon angular movement of the ship under the drag line, is an electric switch shown in the form of an arm 38 having its end attached to the drag line 30 and being movable between two stationary contacts 39 and 40. This switch, together with arm 37, is mounted on a suitable pedestal support 38' (Fig. 3) secured on the deck of the ship and preferably, as shown, at 35 some point on the keel line. The switch is in the control circuit of an electric servo motor 41, shown as a series motor, which is operatively connected through a reducing gear train 42 to a shaft 43 (Fig. 2) aligned with link 28. Shaft 43 is provided with a screw 44 which cooperates with a nut 45 attached to a rectangular table or plate 46, whereby the plate may be given movement of translation in one direction or the other by the electric motor. Cooperating with the upper surface of plate 46 is an electromagnet 47 which when deenergized is adapted to slide in suitable guides longitudinally of plate 46. The electromagnet is operatively connected 40 through a link 48 to the right hand end of lever 30, and is shown connected at a point coincident with the connection of link 28 with lever 30. By energizing electromagnet 47, the servo motor may be operatively connected to lever 30. It then controls the hydraulic rudder actuating mechanism.

A follow up mechanism is provided for servo motor 41 whereby the position of arm 37 is temporarily changed upon operation of the motor so as to move the inboard end of the drag line and disengage contact arm 38 from its stationary contact to open the motor circuit. This mechanism comprises a link 50 connecting plate 46 to an arm 51 60 which is rigidly secured to a rotatably

mounted shaft 52 (Fig. 3) extending upward through the deck of the ship and to which arm 37 is also secured. An electric brake 53 operated by a solenoid 54 is provided for motor 41. This brake may be of any suitable form in which the brake is released upon the energization of solenoid 54 and applied when the solenoid is deenergized.

Referring to Fig. 5, the servo motor 41 is provided with two field coils 55 and 56 which are oppositely wound and hence adapted to operate the motor in opposite directions. The connection of the motor with a suitable source of electrical supply 59 is controlled 80 through two contactors 57 and 58 so as to selectively include the field coil giving the proper direction of rotation. Brake solenoid 54 is also included in the motor circuit. Contactors 57 and 58 are actuated by operating 85 coils 60 and 61, the energization of which is selectively controlled by switch arm 38. A control circuit is provided for electromagnet 47. This circuit includes a switch 62 located adjacent the wheel 20 so that it may be conveniently opened or closed by the helmsman.

The operation of my invention will best be understood by reference to the elementary form thereof shown diagrammatically in Figs. 6 and 7, which form is adaptable for 95 use on certain vessels, such as motor boats, where the pull exerted by the drag can be made of sufficient strength to operate the tiller directly. In this form of my invention the tiller 11 is operatively connected to the 100 drag line which is secured to the ship at a fixed point 35' lying on the keel line of the ship. The ship is first laid on the predetermined course by hand control until the drag follows in the wake of the ship, as shown in Fig. 6, when the steering may be turned over to the drag line. Upon deviation of the ship from the predetermined course, for example, to the left or port, the tiller will be moved to give the proper compensating rudder adjustment, as shown in Fig. 7. It will be observed that the deviation of the ship and the corrective movement given the rudder are proportional in both amount and velocity.

With the arrangement illustrated in Figs. 115 1 to 5 inclusive, the ship is first controlled manually by means of wheel 20 until it has been adjusted accurately on the predetermined course and held there sufficiently long to bring the drag in the wake of the ship. Previous to this setting of the ship, magnet 47 is deenergized by opening switch 62 so that during the manual control of the ship the magnet is free to slide on plate 46 to permit independent movement of member 27 under the control of wheel 20. As the drag swings into position in the wake of the ship, the servo motor 41 tends to keep arm 37 in such position that switch arm 38 does not touch either of its cooperating fixed contacts,

and the final position of arm 37 will depend on the amount of leeway allowance taken into consideration in the rudder adjustment. For zero leeway, arm 37 will take a position 5 along the keel line of the ship. After the ship has been brought on the predetermined course, assuming no leeway allowance, the various parts of the system will be as shown in Fig. 1 of the drawing, control rod 18 being in a central position such that pump 16 is inoperative.

For automatic steering switch 62 is now closed to energize magnet 47 which clamps firmly on table 46, thus establishing a definite 15 length of operating connection between servo motor 41 and lever 30. Upon a slewing movement of the ship from its course, for example, to the left or port, by an amount greater than the freedom of movement provided for contact arm 38, the contact arm 20 will be moved to engage contact 40, as shown in Fig. 5. A circuit is thus closed for operating coil 60 which picks up contactor 57 closing the circuit for servo motor 41 through field coil 55. Brake solenoid 54 is 25 at the same time energized and the brake released. The servo motor now operates in a direction to move plate 46 toward the starboard side, which movement is communicated 30 through link 48 and lever 30 to valve rod 18, whereby pump 16 is caused to actuate piston 10 so as to move tiller 11 in a counterclockwise direction and thus compensate for the deviation of the ship. Through the follow 35 up device for servo motor 41, plate 46 moves with it arm 37 in a clockwise direction tending to cause contact arm 38 to disengage stationary contact 40, whereby the servo motor is brought to rest when it has responded in proportion to the swinging movement of the ship. The circuit for the servo 40 motor may be and usually is broken before the rudder has been completely adjusted by hydraulic piston 10. The object in breaking 45 in this manner the circuit of the servo motor in response to its own movement rather than subsequently in response to the swing of the ship back on the course is to prevent excessive corrective movement of the rudder. 50 Without this arrangement the ship might be subjected to a series of swinging movements, while with it the ship is quickly brought back on the course.

As the ship swings back on the course, 55 contact arm 38 will be moved to engage contact 39, whereby the supply circuit will be closed for operating coil 61 which picks up contactor 58, closing the servo motor circuit through field coil 56. The servo motor now 60 operates in the opposite direction moving plate 46 back toward its initial position until stopped by the opening of its circuit by return movement of arm 37. Pump 16 is thereby controlled so as to straighten the rudder 65 by a small amount. The servo motor will

be controlled in this manner to gradually straighten the rudder by a number of relatively small movements until when the ship has been brought back on the course, the rudder and the various parts of the control 70 system will be in their initial positions as shown in Fig. 1. Upon swing of the ship toward the starboard side, contact arm 38 will be moved into engagement with contact 39 whereby the servo motor will be controlled to give the proper adjustment of the rudder, which will be gradually straightened with the return movement of the ship, 75 as will be understood from the previous description.

It will be observed that the ship will not only be properly controlled in direction, but also in position with relation to any course on which it may be originally laid. If the ship should be displaced in position to one 80 side or the other of the predetermined course, the drag line will extend at an angle with the center line of the ship, since the drag will still follow on the predetermined course, or very nearly so. Contact arm 38 85 will therefore be actuated to correct the positional displacement of the ship.

The amount of clearance between contact arm 38 and contacts 39 and 40 will vary with the particular conditions of navigation 90 encountered, and will be as small as practicable. For example, sufficient freedom will ordinarily be provided to prevent contact from periodic yaw of the ship due to the swell of the ocean. In extremely rough seas control 95 of the ship by the automatic steering system may be impracticable, and in this event switch 62 will be opened and hand steering resorted to.

The speed of the servo motor is 100 such that the rudder is moved at a velocity greater than the highest possible velocity of 105 swing of the ship. In case of a persistent swing of the ship of considerable duration the servo motor, therefore, will operate for 110 a number of short periods, thus causing the rudder to be adjusted in steps, the duration of each step depending on the velocity of 115 swing of the ship. Consequently, the rudder which is proportional to the velocity of the ship's swing causing the movement.

It will be observed that any movement applied to lever 30 by servo motor 41 will be transmitted to member 30 of the hydraulic 120 repeater system whereby wheel 20 will be actuated so as to always indicate the position of the rudder. The position and movements of the wheel therefore provide a convenient check on the automatic system.

Referring to Fig. 8, in certain cases it may be desirable to connect arm 51 through link 50 with the tiller 11, as shown in this modification of my invention. By means of this arrangement the breaking of the circuit 130

for the servo motor is made directly responsive to the rudder adjustment, although as in the arrangement previously described, it is not dependent on the response of the ship 5 to the adjusted position of the rudder.

As shown also in Fig. 8, arm 38 may be provided with a pointer 65 which cooperates with a stationary arc shaped scale 66, suitably calibrated in degrees, and indicates on 10 the scale the angle between the drag line and the keel line of the ship. This angle, it will be observed, is an indication of the amount of leeway allowance being made by the ship. The indicator may be provided for the 15 convenience of the skipper.

It will be observed that by means of my invention, I am enabled to utilize a controlling force, viz; the pull of the drag line, which is constantly applied and hence 20 constantly available, as distinguished from control systems, such as those employing a gyrocompass, wherein the controlling force is zero under stable conditions and must be built up, whereby an appreciable time lag 25 is introduced.

While I have described my invention as embodied in concrete form and as operating in a specific manner in accordance with the provisions of the patent statutes, it 30 should be understood that I do not limit my invention thereto, since various modifications thereof will suggest themselves to those skilled in the art without departing from the spirit of my invention, the scope of 35 which is set forth in the annexed claims.

What I claim as new and desire to secure by Letters Patent of the United States, is:

1. Automatic steering means for a dirigible craft comprising a slender elongated 40 member towed by said craft and thereby caused to take up a position defining a predetermined course for said craft, and steering means for said craft controlled by said member upon deviation of said craft from said course, whereby said craft is maintained on said course.

2. The combination with a ship, of automatic steering means therefor, comprising a drag line towed by said ship, and steering 50 means controlled by said drag line upon deviation of said ship from a predetermined course so as to return said ship to said course.

3. Automatic steering apparatus for a self-propelled ship, comprising a drag, a line connecting said drag to the ship, and steering means for the ship controlled by said line upon swinging movement of the ship so as to maintain the ship on a predetermined course.

4. Automatic steering means for a ship comprising a drag, a line connecting said drag to the ship, steering means for the ship, a motor for operating said steering means, 65 and control means for said motor respon-

sive to swinging movement of the ship with relation to said line so as to maintain the ship on a predetermined course.

5. The combination with a ship, of automatic steering means therefor, comprising a drag line, operating means for the rudder of said ship, a motor for controlling said operating means, and control means for said motor actuated by said drag line upon swinging movement of said ship so as to return 75 said ship to a predetermined course.

6. The combination with a ship, of automatic steering means therefor, comprising operating means for the rudder of said ship, control means therefor, an electric motor 80 operatively connected to said control means, a drag line, and control means for said motor operated by said drag line in response to swinging movement of said ship, whereby said ship is automatically returned to a pre- 85 determined course.

7. The combination with a ship, of automatic steering means therefor comprising operating means for the rudder of said ship, control means therefor, a drag line, secondary operating means controlled by said drag line in response to swinging movement of said ship, and a releasable operating connection between said secondary operating 90 means and said control means whereby said 95 steering means may be independently adjusted to bring the ship on a predetermined course.

8. The combination with a ship, of automatic steering means therefor, comprising 100 operating means for the rudder of said ship, control means therefor, a drag line, a motor controlled by said drag line in response to swinging movement of said ship, an operating connection between said motor and 105 said control means including an electromagnet, and means for deenergizing said electromagnet for independent control of said ship and for energizing said electromagnet 110 for automatic control of said ship.

9. The combination with a ship, of automatic steering means therefor comprising operating means for the rudder of said ship, control means therefor, a drag line, a motor controlled by said drag line in response to 115 swinging movement of said ship, and an operating connection between said motor and said control means including an electromagnet adapted when deenergized to permit independent adjustment of said rudder for 120 any predetermined course and when energized to establish an operating connection between said motor and said control means whereby said rudder is automatically adjusted so as to hold said ship on said predetermined course.

10. The combination with a ship, of automatic steering means therefor, comprising operating means for the rudder of said ship, control means therefor, a drag line, a motor 130

controlled by said drag line in response to swinging movement of said ship, a plate reciprocated by said motor, an operating arm connected to said control means, and an electromagnet secured to said arm and resting on said plate so as to be free to slide thereon when deenergized to permit independent adjustment of said rudder for any predetermined course and establishing when

energized an operating connection between 10 said motor and said control means whereby said rudder is automatically adjusted so as to hold said ship on said predetermined course.

In witness whereof, I have hereunto set 16 my hand this 17th day of March, 1922.

ROBERT H. ROGERS.
